UNITED STATES PATENT OFFICE.

NORA RETTIG, OF LOGANSPORT, INDIANA.

FLY-PAPER HOLDER.

1,261,618.

Specification of Letters Patent.

Patented Apr. 2, 1918.

Application filed March 30, 1917. Serial No. 158,659.

To all whom it may concern:

Be it known that I, NORA RETTIG, a citizen of the United States, residing at Logansport, in the county of Cass and State of Indiana, 5 have invented new and useful Improvements in Fly-Paper Holders, of which the following is a specification.

This invention comprehends improvements in holders for fly paper and has for one of 10 its objects the provision of an extremely simple and practical device which may be suspended from a wall or ceiling.

Another and more specific object of the invention is to provide a fly paper holder 15 having a plate on which are mounted spring clips for holding the fly paper thereagainst and having a pair of bails or hangers for attachment to a horizontal or vertical hook for supporting the device, said hangers being provided with means for clamping them in planes parallel with the plate.

The invention also aims to generally improve devices of this nature to render them more practical, useful and commercially 25 desirable.

With these and other objects in view as will become more apparent as the description proceeds, the invention consists in certain novel features of construction, combination and arrangement of parts as will be 30 hereinafter fully described, illustrated and claimed.

In the drawings,

Figure 1 is a perspective view showing 35 the fly paper holder in use and secured to a wall.

Fig. 2 is a fragmentary plan view of the holder showing one of the bolts clamped against the plate.

40 Fig. 3 is a fragmentary sectional view on the plane of line 3—3 of Fig. 2, and

Fig. 4 is a detail view of a part to be hereinafter described.

Referring in detail to the drawings by 45 numerals, 1 designates a plate preferably formed of tin and substantially equal in width to a sheet of fly paper 2 which is held thereagainst by a pair of U-shaped spring clips or fasteners 3 which are provided 50 with spring coils 4 and which are soldered or otherwise suitably secured to the plate. The plate is somewhat longer than the standard sheet of fly paper and is bent back on itself adjacent its end edges 55 to provide reinforcements and to overcome

the disadvantages of having sharp exposed edges.

The plate is provided with lateral flanges 6, 7 formed by bending the top of the plate at right angles to the main portion thereof 60 and then bending the bent portions back on themselves.

A pair of handles or bails 8 of U-shaped formation are pivotally secured to the flanges 6 and 7 by having the ends of their 65 arms 9 hooked through openings 10 in the flanges as indicated by the numeral 11. The central portions 12 of the bails or handles are bent to provide the eyes 13. One arm of each of the bails is bent to provide a spring 70 coil 14 lying in a plane substantially parallel with the arm. Said coil is formed at the outer terminal of the arm and is disposed to one side of the plane of the bail or handle.

The bails or handles when swung against 75 the plate are held in this position by the coils 14 and arms 9 which clamp between them the flange 6 of the plate. It will be noted on reference to Fig. 3 that this flange does not extend the full length of the plate 80 but is of such a length as to terminate substantially centrally of the coils 14 when the handles are disposed against the plate.

When it is desired to secure the device to a wall or other vertical support, the handles 85 are swung upwardly toward each other to dispose the loops 14 in substantial alinement with each other for connection to a hook 15. The device may be secured to a ceiling or horizontal support by hooking eyes 13 to a 90 suitable fastener.

From the foregoing description taken in connection with the accompanying drawings, it will be seen that I have provided a very simple and practical fly paper holder 95 to which sheets of fly paper may be removably secured and which has swinging bails or handles which may be clamped into inoperative out of the way position against the body of the device or which may be secured 100 to horizontal or vertical fastening means for supporting the holder in operative position.

The coils 14 form an important feature of the device since it is essential that some 105 means be provided for securing the handles against movement when not in use and when the device is being shipped or moved from place to place.

While I have shown and described the 110

preferred embodiments of my invention, it will be clearly understood that I do not wish to be limited to this construction, but may make such changes as will fall within the scope and spirit of the invention as claimed.

What I claim is:

1. A fly paper holder comprising a plate adapted to hold sheets of fly paper, clamp projecting flanges formed on the sides of 10 said plate, a pair of U shaped handles having the free ends of their arms pivotally secured to said plate and spring coils formed on said handles for clamping engagement with said flanges whereby the handles may be held in an out of the way inoperative position, the coils registering when the handles are in elevated positions to provide for engagement with a support.

2. A fly paper holder comprising a plate adapted to hold sheets of fly paper, laterally 20 projecting flanges formed on said plate, a pair of U shaped handles having the free ends of their arms pivotally connected to said flanges, the handles being adapted to lie against the plate at an angle thereto and 25 spring coils formed on said handles in a plane substantially parallel to the arms thereof for clamping engagement with one of said flanges whereby the handles may be held in an out of the way position, the coils 30 registering when the handles are in elevated positions to provide for engagement with a support.

In testimony whereof I affix my signature.

MRS. NORA RETTIG.
